[57] CLAIM

The ornamental design for an identification tag for electric wire, as shown and described.

DESCRIPTION

FIG. 1 is a top plan view of an identification tag for electric wire showing our new design;

FIG. 2 is a bottom plan view;

FIG. 3 is a front elevational view;

FIG. 4 is a rear elevational view;

FIG. 5 is a right side elevational view, a left side view being substantially identical;

FIG. 6 is a sectional view along line 6—6 of FIG. 3;

FIG. 7 is a sectional view taken along line 7—7 of FIG. 3; and,

FIG. 8 is a reduced perspective view thereof, with the broken line showing for illustrative purposes only and forming no part of the claimed design.

FIG. 1

FIG. 2

FIG. 6

FIG. 3

FIG. 4
